UNITED STATES PATENT OFFICE

108,757

DESIGN FOR A COMBINED CAP AND MUFFLER

Louis Tannenbaum, Hoboken, N. J.

Application February 15, 1938, Serial No. 75,151

Term of patent 3½ years

To all whom it may concern:

Be it known that I, Louis Tannenbaum, a citizen of the United States of America, residing in Hoboken, in the county of Hudson and State of New Jersey, have invented a new, original, and ornamental Design for a Combined Cap and Muffler, of which the following is a specification, reference being had to the accompanying drawing, forming part thereof, wherein,

The figure is a perspective view of a combined cap and muffler showing my new design.

I claim:

The ornamental design for a combined cap and muffler, substantially as shown.

LOUIS TANNENBAUM.
